UNITED STATES PATENT OFFICE.

DANIEL EDWARD WATERS, OF ST. PAUL, MINNESOTA.

DISPLAY-SIGN.

1,313,434.

Specification of Letters Patent.

Patented Aug. 19, 1919.

Application filed June 17, 1918. Serial No. 240,379.

To all whom it may concern:

Be it known that I, DANIEL EDWARD WATERS, of the city of St. Paul, in the State of Minnesota, United States of America, 5 have invented certain new and useful Improvements in Display-Signs, of which the following is the specification.

The invention relates to improvements in display signs and the principal object of the 10 invention is to provide a moving sign which, by virtue of its movement, will attract the attention of the public, thereby rendering the sign a valuable one for display purposes.

A further object of the invention is to provide a sign particularly adapted for outdoors and which, when once set in operation, 15 will continue the work without further attention.

A still further object is to construct a 20 moving sign in a comparatively inexpensive, and durable manner and so that it can be readily erected and put into operation.

With the above general objects in view the invention consists essentially in a sign board 25 frame having a centrally positioned stationary sign board, movable sign boards mounted in the frame and shiftable from side to side of the stationary sign and means for shifting the movable signs at predetermined instants, the parts being arranged and constructed as hereinafter more particularly described and later pointed out in the appended claims, reference being had to the accompanying drawing in which:—

30 Figure 1 represents a front view of my complete sign board.

Fig. 2 represents a horizontal sectional view through the sign board with parts broken away, the section being taken in the 40 plane denoted by the line X—X' Fig. 3.

Fig. 3 represents a vertical sectional view through the sign board with the central part of the board broken away, the section being taken in the plane denoted by the line Y—Y'

45 Fig. 2.

Fig. 4 represents a side view of the driving parts.

Fig. 5 represents an enlarged detailed 50 vertical sectional view through the top part of the sign board.

Fig. 6 represents an enlarged detailed longitudinal sectional view through the pinions and pulleys on the counter shaft.

In the drawing like characters of reference indicate corresponding parts in the 55 several figures.

1 represents a sign board frame carried by suitable legs 2 and formed from top and bottom beams 3 and 4 closed at the ends by end posts 5 and 6. Suitable molding pieces 7 60 and 8 border the front exposed area of the sign and cross strips 9 and 10 are secured to the front of the sign board and divide the frame, in the present instance, into three equal sized exposure areas 11, 12 and 13. In 65 the exposure area 11 I place a permanent or stationary sign board 14 on which any suitable advertising material appears. This sign board is located at the front of the frame.

15 and 16 are movable sign boards mounted in the frame 1 for in and out movement in respect to the sign board 14 and in this connection it is to be noticed that the said movable sign boards are positioned to pass one 70 another in movement and in a location behind the permanent sign board. In actual practice the sign boards 15 and 16 are of a length such that when fully extended their outer ends fully close the display areas 12 and 13 75 and their inner ends lie behind the board 14 and are of the full length and width of such board.

To render the signs 15 and 16 readily 80 movable I have fitted their upper and lower edges with rollers 17 which operate in upper and lower guiding grooves 18 and 19, 20 and 21 formed in the beams 3 and 4 and passing the full length thereof.

On the front faces of the sign boards 15 90 and 16 I desire to place two distinct advertisements, these being arranged such that when the outer ends of the said boards are fully extending, as shown in Fig. 1, the advertising material on the outer ends of 95 said signs appears in the exposure areas 12 and 13 and the advertising material on the front face of the inner ends of the said signs is not exposed, being entirely covered by the permanent sign 14.

According to this arrangement it will be obvious that by manipulating the movable sign boards I can alternately expose the signs on the movable sign boards and thereby catch the eye of the public.

In order to operate the movable sign

boards I have supplied the driving device now described.

To the rear of the sign I locate a platform 22 on which I mount a prime mover such as 5 an electric motor 23 of which 24 is the motor shaft. The motor shaft is extended and carries a comparatively long driving pulley 25 and on this pulley I mount a belt 26 which drives a pulley 27 located at the end 10 of what might be termed a timing shaft 28 which is carried by suitable bearings mounted on the platform. A bevel pinion 29 is secured to the timing shaft and meshes with a further bevel pinion 30 located at the end 15 of a short shaft 31 carried by a pedestal 32 mounted on the platform.

33 is a cam secured to the shaft 31 and for the greater part circular but having at 20 a lug 35.

36 represents a counter-shaft which is split centrally into two sections indicated at 36' and 36''. The counter shaft is carried by suitable bearings and is fitted centrally with 25 a loose pulley 37 which is located centrally between two fixed pulleys 38 and 39 secured respectively one to the shaft section 36' and the other to the shaft section 36''. Oppositely disposed equal sized bevel pinions 40 30 and 41 are also secured permanently one to the shaft section 36' and the other to the shaft section 36'' and said pinions both mesh with a bevel gear 42 carried by an adjacent pedestal 43. A belt 44 extends normally between the pulley 25 and the pulley 37. The cam 33 is utilized to shift the belt 44 and the shifting is accomplished by a slidably mounted rod 45 having the one end supplied with a roller 46 which rides the face of the 40 cam and the other end provided with a spanner 47 which spans the belt. A spring 48 is connected to the end of the rod next the cam to hold the roller continuously on the cam.

From this arrangement it will be apparent 45 that as the pulley 25 is rotated the belt 26 will operate the cam and the cam in turn will operate the rod to shift the belt alternately first from the idle pulley 37 on to the pulley 38, then back to the idle pulley and 50 after an interval of time over on to the pulley 39 and then back to the idle pulley, such movement occurring in one revolution of the cam.

During the interval that the belt is driving 55 the pulley 38 the shaft 36 is driven in one direction while when the belt is on the pulley 39 the drive is in the opposite direction. The idle intervals between the reversals of the drive occur when the belt is on the idle pulley and the length of the interval is determined by the design of the cam as no movement will be effected in the shifting rod until the roller passes into the slot or engages the lug.

60 65 This driving device is connected directly

with the sign board as the inner end of the shaft 36 is fitted with a bevel pinion 49 which meshes with a bevel pinion 50 located at the lower end of a vertically disposed operating shaft 51 located centrally between the sign boards 15 and 16 in a position centrally behind the fixed sign board 14. The shaft 51 is fitted with upper and lower pinions 52 and 53 which operate on lengthwise extending racks 54 and 55 permanently secured to the inner faces of the moving sign boards. 75

From the above disclosure it will be seen that when this sign board is set up and the motor is started the moving signs will remain inert for a period and will then be 80 shifted.

A person observing the sign will first see the advertising material exposed as shown in Fig. 1 and then if he waits for a short time he will notice the signs changing. That is to say, he will see the previously exposed material on the sign boards 15 and 16 gradually moving in behind the central stationary sign and new advertising material coming 90 into view and gradually being fully exposed in the space previously occupied by the original material.

While I have shown and described a special driving device for operating and timing the device, still it will be understood that this could be readily modified without in the least departing from the spirit of my invention as it is simply an intermittent forward and reverse driving arrangement for the 100 moving signs.

What I claim as my invention is:—

1. In a display sign, a stationary sign board and horizontally movable sign boards associated with the stationary sign board and designed to be withdrawn behind and projected to each side of the stationary display sign board. 105

2. In a display sign, a central stationary sign board, a pair of shifting sign boards associated with the stationary sign board and of twice the length of the stationary sign board and means for shifting the movable sign boards to alternately expose beyond the stationary sign board one-half of each shifting sign. 110

3. In a display sign, a substantially rectangular frame, a stationary sign board located centrally of the frame, horizontally shifting sign boards slidably mounted in the frame and means for operating the shifting sign boards to alternately withdraw and expose them at opposite ends of the stationary sign board. 115

4. In a display sign, a substantially rectangular frame, a stationary sign board located centrally of the frame and providing exposure areas at the ends of the frame, a pair of shifting sign boards slidably within the frame and mounted to pass clear of one 120 125 130

another behind the central sign and means for sliding the shifting sign boards alternately in and out to expose them in the exposure areas at the ends of the central sign board.

5. In a display sign, a substantially rectangular frame, a stationary sign board located centrally of the frame and providing similar exposure areas at the ends of the frame, a pair of shifting sign boards slidably mounted in the frame and each twice the length of the stationary frame and

mounted to pass one another when moved endwise within the frame and driving means for intermittently operating the movable 15 sign boards to alternately expose the ends thereof in the exposure areas at the ends of the central sign board.

Signed at St. Paul, this 11 day of May 1918.

DANIEL EDWARD WATERS.
